CLAIM

We claim the ornamental design for a stile, as shown and described.

DESCRIPTION

FIG. 1 is a perspective view of a design for a stile;
 FIG. 2 is a front view thereof;
 FIG. 3 is a rear view thereof;
 FIG. 4 is a top view thereof, a bottom view being a mirror image of the FIG. 4 top view thereof;
 FIG. 5 is a side view thereof, an opposite side view being a mirror image of the FIG. 5 side view thereof;
 FIG. 6 is a fragmentary view taken from an area of FIG. 2 marked as "A" and illustrating a corner thereof;
 FIG. 7 is a sectional view taken along sectional lines 7-7 of FIG. 2 thereof;
 FIG. 8 is a sectional view taken along sectional lines 8-8 of FIG. 2 thereof;
 FIG. 9 is a sectional view taken along sectional lines 9-9 of FIG. 2 thereof; and,
 FIG. 10 is a sectional view taken along sectional lines 10-10 of FIG. 2 thereof.

The stile is shown with a symbolic break in its length. The appearance of any portion of the article between the break lines forms no part of the claimed design.
